UNITED STATES PATENT OFFICE.

VICTOR E. ADLER, OF LOS ANGELES, CALIFORNIA.

BANJO-HEAD SUPPORTS.

Application filed April 13, 1925. Serial No. 22,756.

To all whom it may concern:

Be it known that I, VICTOR E. ADLER, a citizen of the United States, residing at Los Angeles, in the county of Los Angeles and State of California, have invented new and useful Improvements in Banjo-Head Supports, of which the following is a specification.

This invention relates to improvements in 10 banjos and devices for supporting the heads upon banjos.

An object of this invention is to provide a device adapted to be readily applied to 15 banjos and similar musical instruments, which will support the head of the banjo in such a manner as to greatly improve the quality of tone of the banjo.

With the foregoing and other objects in 20 view which will be made manifest in the following detailed description and specifically pointed out in the appended claims, reference is had to the accompanying drawings for an illustrative embodiment of the invention, wherein:

25 Figure 1 is a top plan view, parts being broken away, of the base or body of a banjo to which the improvement has been applied;

Fig. 2 is a vertical section taken substantially on the line 2—2 of Fig. 1;

30 Fig. 3 is a plan view of the device which is applied to the banjo;

Fig. 4 is a vertical section taken on the line 4—4 of Fig. 3;

35 Fig. 5 is a plan view of the supporting ring which is supported upon the device shown in Fig. 3; and

Fig. 6 is a vertical section taken on the line 6—6 of Fig. 5.

Referring to the accompanying drawings 40 wherein similar reference characters designate similar parts throughout, the banjo is shown as consisting of the annular body 10, to which the neck or finger board 11 is secured, carrying the frets 12. Collars 13 are provided with pins 14 which extend 45 through the annular body and are secured therein as by nuts 15 or the like. Hooks 16 have their lower ends extending through the collars 13 and are adjustable as by nuts 17. The annular body 10 in the conventional 50 form of banjo is formed of wood, although it may be formed from other materials as well.

55 My improvement consists of a head supporting device, generally indicated at 18. This device consists of an outer ring 19 and

an inner ring 20 having a flange 21 which extends toward the outer ring. Radial webs 22 connect the outer ring 19 and the inner ring 20 above the flange 21. The top edges 60 of the webs 22 are flush with the top edge of the outer ring 19, whereas the top edge of the inner ring 20 extends slightly above the top edges of the webs. Recesses 23 are formed in the top edges of the radial webs 65 22 and are adapted to receive the supporting ring 24 which supports the head 25. The head is being shown as stretched by means of a tension band 26 which is drawn downwardly over the outside surface of the 70 outer ring 19 by the hooks 16. The height of the supporting ring 24 is such that it will maintain the head 25 slightly above the top edge of the inner ring 20. Apertures 27 are formed in the inner ring 20 between the 75 radial webs 22. As clearly illustrated in Fig. 2, the lower edges of the webs 22 rest upon the top edge of the annular body 10 with the lower edges of the outer ring 19 bearing against the outside surface of the 80 annular body and the edge of the flange 21 bearing against the inside surface of the body. In this manner the head supporting device 18 rests upon the annular body upon its radial webs 22. In the preferred form 85 of construction, the head supporting device 18 has its outer ring 19, the inner ring 20 with its annular flange 21, and the connecting webs 22 formed integral with each other. These parts may be formed from a single in 90 tegral casting of aluminum. The supporting ring 24 is preferably formed of a high grade mahogany, and is formed of a plurality of plies indicated at 28 and 29 respectively. Each of the plies is formed of 95 a plurality of arcuate segments, as shown upon the drawing, and these segments are so arranged that the joints in the upper ply 28 are staggered with respect to the joints in the lower ply 29. 100

By the improved head supporting device, the vibrations created by the head 25 when one of the strings S is picked or struck will be so amplified or transmitted through the supporting ring 24 and the head supporting 105 device 18, that a much finer quality of tone is developed from the banjo than from banjos heretofore employed. I have found that a loud banjo will be produced if the apertures 27 are comparatively large, whereas if the apertures 27 are comparatively small, the banjo will not become quite so loud. By 110

the improved construction not only will the tone of the banjo be increased, but the length of a note produced by a single striking of one of the strings will greatly be prolonged, so that a much finer and a much more highly desired banjo is produced by the application of the improved head supporting device. It will be understood that by making the head supporting device of various sizes that they may be applied to any conventional type of banjo, so that it is unnecessary to construct a banjo which is especially constructed to receive the head supporting device.

15 It will be understood that various changes in the detail of construction may be made without departing from the spirit or scope of the invention as defined by the appended claims.

20 I claim:

1. In a banjo, an annular body and a head supporting device supported upon said body comprising an outside ring, an inside ring, webs connecting said rings and resting upon the top of said body, a supporting ring resting upon the top of said webs, and a head supported upon said supporting ring.

2. In a banjo, an annular body and a head supporting device supported upon said body comprising an outside ring, an inside ring, webs connecting said rings and resting upon the top of said body, a supporting ring resting upon the top of said webs, and a head supported upon said supporting ring, there being apertures formed in said inside ring between said webs.

3. In a banjo, an annular body, and a head supporting device resting upon said body, said head supporting device comprising an outside ring, an inside ring having a flange extending toward the outside ring engaging the interior surface of the body, webs connecting said rings and resting upon the top edge of the body, and a supporting ring resting upon said webs supporting the head of the banjo.

4. In a banjo, an annular body and a head supporting device resting upon said body, said head supporting device comprising an outside ring, an inside ring having a flange extending toward the outside ring engaging upon the interior surface of the body, webs connecting said rings and resting upon the top edge of the body, and a supporting ring resting upon said webs supporting the head of the banjo, there being apertures formed in said inside ring between said webs.

5. A head supporting device for banjos comprising an outside ring, an inside ring, webs connecting the rings, and a supporting ring resting upon said webs.

6. A head supporting device for banjos comprising an outside ring, an inside ring, webs connecting the rings, and a supporting ring resting upon said webs, said supporting

ring being of a plurality of plies and being formed in segments.

7. A head supporting device for banjos comprising an outside ring, an inside ring having a flange extending toward the outside ring engageable upon the interior surface of the body of a banjo, webs connecting the rings above said flange, and a supporting ring resting upon said webs, there being apertures formed in said inside ring between said webs.

8. A head supporting device for banjos comprising an outside ring, an inside ring having a flange extending toward the outside ring engageable upon the interior surface of the body of a banjo, webs connecting the rings above said flange, there being recesses formed in the top edges of said webs, and a supporting ring disposed within said recesses constituting a support for the head of the banjo.

9. A head supporting device for banjos comprising an outside ring, an inside ring having a flange extending toward the outside ring engageable upon the interior surface of the body of a banjo, webs connecting said rings, the top edges of said webs being flush with the top edges of said outside ring, the top edge of said inside ring extending slightly above the top edges of said webs, there being recesses formed in the top edges of said webs, and a supporting ring disposed within said recesses and having its top edge slightly above the top edge of said inside ring, said supporting ring constituting a support for the head of the banjo.

10. A head supporting device for banjos comprising an outside ring, an inside ring having a flange extending toward the outside ring engageable upon the interior surface of the body of a banjo, webs connecting said rings, the top edges of said webs being flush with the top edges of said outside ring, the top edge of said inside ring extending slightly above the top edges of said webs, there being recesses formed in the top edges of said webs, and a supporting ring disposed within said recesses and having its top edge slightly above the top edge of said inside ring, said supporting ring constituting a support for the head of the banjo and being formed of a plurality of plies.

11. A head supporting device for banjos comprising an outside ring, an inside ring having a flange extending toward the outside ring engageable upon the interior surface of the body of a banjo, webs connecting said rings, the top edges of said webs being flush with the top edges of said outside ring, the top edge of said inside ring extending slightly above the top edges of said webs, there being recesses formed in the top edges of said webs, and a supporting

- ring disposed within said recesses and having its top edge slightly above the top edge of said inside ring, said supporting ring constituting a support for the head of the banjo, there being apertures formed in said inside ring between said webs.
12. A head supporting device for banjos comprising an outside ring, an inside ring having a flange extending toward the outside ring engageable upon the interior surface of the body of a banjo, webs connecting said rings, the top edges of said webs being flush with the top edges of said outside ring, the top edge of said inside ring extending slightly above the top edges of said webs, there being recesses formed in the top edges of said webs, and a supporting ring disposed within said recesses and having its top edge slightly above the top edge of said inside ring, said supporting ring constituting a support for the head of the banjo, said inside and outside rings and webs being formed integral with each other.
- 10 In testimony whereof I have signed my name to this specification.

VICTOR E. ADLER.
